UNITED STATES PATENT OFFICE.

CHARLES J. KLEIN, OF MILWAUKEE, WISCONSIN.

LAMP-SOCKET CASING OR THE LIKE.

1,235,531.

Specification of Letters Patent. Patented July 31, 1917.

Application filed December 8, 1913. Serial No. 805,289.

To all whom it may concern:

Be it known that I, CHARLES J. KLEIN, a citizen of the United States, residing at Milwaukee, in the county of Milwaukee and State of Wisconsin, have invented new and useful Improvements in Lamp-Socket Casings or the like, of which the following is a full, clear, concise, and exact description, reference being had to the accompanying drawing, forming a part of this specification.

This invention relates to casings for lamp sockets or the like, and more particularly to interlocking means for the sections of such casings.

One of the objects of my invention is to provide an improved and reinforced interlocking means to detachably hold a casing cap and shell against relative separation and rotation.

Further objects and advantages will appear hereinafter.

The accompanying drawing illustrates the preferred embodiment of my invention.

Figure 1 is a side elevation of a lamp socket casing wherein the interlocking means is employed for the cap and shell;

Fig. 2 is a similar view of a pendent switch casing;

Fig. 3 is an enlarged detail view of the interlocking means showing the parts thereof separated;

Fig. 4 is a perspective view of the same; and,

Fig. 5 is a central longitudinal section through the interlocking means with the parts in engagement.

Each of the casing illustrated comprises a cap 1 and a resilient shell 2 of suitable metal and design. The shell 2 telescopes within a cylindrical rim 3 of the cap and abuts an annular shoulder 4 of the latter. The overlapping ends of the sections carry interlocking shoulders to retain the parts against relative movement.

This interlocking means comprises catches 5 on one part, preferably the cap, and cooperating shoulders 6 on the other. In practice, two oppositely disposed sets of co-operating catches and shoulders are employed.

The structure and arrangement of the interlocking means are clearly shown in Figs. 3, 4, and 5. As there indicated, the catch 5 is spaced from the margin of the cap and formed by crimping inwardly and upwardly a segmental portion of the wall 3 at one side

of a transverse slit 7. The catch thus comprises an upper bearing surface 8 and converging side walls 9 integral and continuous with the cap rim. The upper bearing surface 8 is preferably inclined to meet the interior of the wall 3 at a slightly acute angle, while the free edges 10 of the side walls 9 are inherently tapered from the tip of the catch to the wall 3 at the ends of the line 7. The edge of the cap thus remains continuous and the strip of metal 11 below each catch serves to strengthen the base of the latter and reinforce the same.

While the shoulders 6 may be formed in various ways, in practice they preferably comprise apertures 12 in the shell corresponding in contour to the segmental conformation of the catches.

The cap and shell may be readily attached by first alining the two sets of interlocking means and then telescoping the parts together. During the latter operation the catches 5 slip over the shell margin and enter the openings 12 with a snap, due to the resiliency of the shell. The bearing surfaces 8 of the catches thereupon abut the upper parts of the shoulders 6 to support the shell. At the same time, the side walls 9 of the catches abut the depending parts of the shoulders 6 to prevent relative rotation of the sections. The cap and shell are thus locked against both axial separation and relative rotation. Moreover, the effectiveness of the axial lock is increased by the inclination of the upper bearing surfaces of the catches, while the effectiveness of the rotary lock is enhanced by the opposed curved side walls of the catches and shoulders.

Furthermore, assembly of the sections of the casing is facilitated by the arrangement of the interlocking means described since the shell may be partially inserted in the cap and the shoulders alined before the margin of the shell abuts the catches 5. Thus any tendency of the cap and shell to slip out of registry during attachment is effectively prevented by the overlapping edges of the two parts.

Separation of the sections is readily obtained by compressing the shell beneath the shoulders 6 until the same are released from the catches, whereupon the shell may be drawn axially from the cap.

Guide notches 13 may be provided in the margin of the shell directly above the shoul-

ders 6. These notches are designed to receive the catches 5 of the cap and thereby further insure positive alinement of the interlocking means to facilitate assembly of the two sections of the casing.

What I claim as new and desire to secure by Letters Patent is:

1. A casing for lamp sockets comprising a cap and a shell adapted to telescopically unite, one of said members having a struck up catch comprising a segmental portion thereof engaging a correspondingly shaped shoulder on the other member to prevent separation of said members, said catch and shoulder being arched to provide a maximum engaging surface opposing relative rotation of the members, and said arched catch having beveled edges formed by the chord edge of said segmental portion.
2. A casing for lamp sockets comprising a cap and a shell adapted to telescopically unite, one of said members having a struck up catch engaging a correspondingly shaped shoulder on the other member, to prevent

separation thereof, said catch and shoulder 25 being arched to provide a maximum engaging surface opposing relative rotation of the members, said catch also being hooked at an acute angle to oppose disengagement thereof from said shoulder.

3. A casing for lamp sockets comprising a cap and a shell adapted to telescopically unite, one of said members having an integral catch inset from its edge and hooked at an acute angle to positively engage with 35 in a correspondingly shaped shoulder on the other member, to lock said members against separation, said catch and shoulder being arched to provide a maximum engaging surface functioning to prevent relative rotation 40 of the members.

In witness whereof, I have hereunto subscribed my name in the presence of two witnesses.

CHARLES J. KLEIN.
